UNITED STATES PATENT OFFICE.

CHARLES E. KUHN, OF HARRISBURG, PENNSYLVANIA.

COMBINATION FURNITURE.

Application filed February 18, 1922. Serial No. 537,567.

To all whom it may concern:

Be it known that I, CHARLES E. KUHN, a citizen of the United States of America, and resident of Harrisburg, in the county of 5 Dauphin and State of Pennsylvania, have invented certain new and useful Improvements in Combination Furniture, of which the following is a specification.

This invention relates to combination 10 furniture for laundry use more particularly, and the said invention has for an object the provision of a novel foldable ironing board, clothes rack and shelving effective to hold clothes after they are ironed, the said shelving being stepped, one with relation to the 15 other, and including novel means by which the shelving is supported.

It is a further object of this invention to produce an article of furniture of the character indicated which can be knocked down or folded in order that it will occupy comparatively small space when stored.

It is a further object of this invention to produce a foldable frame and parts associated with it which can be readily manipulated for the purpose of assembling or dismantling the parts thereof when it is to be used or folded.

With the foregoing and other objects in 30 view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which—

40 Figure 1 illustrates a perspective view of the article of furniture with the shelving in supported positions;

Figure 2 illustrates a perspective view thereof with the shelving removed and the 45 ironing board applied to it;

Figure 3 illustrates a perspective view of the underneath side of the ironing board;

Figure 4 illustrates a perspective view of one of the shelf hangers;

50 Figure 5 illustrates a perspective view of another form of shelf sling or hanger;

Figures 6, 7, 8 and 9 are plan views of the respective shelves.

In carrying the invention into practice, 55 and in the present illustrated embodiment of the invention, the frame comprises four

posts 10, 11, 12 and 13, the posts being in pairs, two at each end.

Each pair of posts, as for instance, the posts 10 and 11, are connected together or 60 braced by rods 14, 15 and 16, but the number of these braces may be increased or diminished, according to the requirements in practice. As a further means for stabilizing the structure, the braces 15 and 16 65 are connected by vertically disposed rods or braces 18 and 19. As the construction of the two ends of the frame is identical, the description of one end will serve as a disclosure to enable one skilled in the art to 70 carry these portions of the invention into practice.

The brace 15 at one end is connected to the brace 14 at the other end and vice versa, by the diagonally disposed struts 20 and 21, 75 the former of which is here shown as having a latch 22 which interlocks with the strut 21 to hold the parts in the position in which they appear in Fig. 1, but the latch, of course, may be disengaged from the strut, 80 so that they may swing on the braces as pivots to permit nesting of the ends when the device is to be stored.

The posts project above the top brace 16, and the posts on one side form anchorages 85 for a shelf 23, by reason of the fact that the said shelf has apertures 24 to receive the upper ends of the posts, whereas the shelf rests on and is wholly supported by the braces 16. The interlocking engagement of 90 the shelf with the posts serves to prevent its dislodgement, and it further has the effect of bracing the end frames, so that they will not have a tendency to spread apart. The shelf 25 comprises a rectangular board or 95 element which has its ends resting in stirrups 26 that have ends 27 partially encircling the brace 16 by which the stirrups are supported, and preferably, the ends of the shelf 25 extend between the vertically disposed braces 18 and 19.

The shelf 27^a is of the same general configuration as the shelf 25, except that its outer corners are notched, as shown at 28, to form clearances for the posts at the side 105 opposite to that to which the shelf 23 is apertured. The shelf 27^a rests on the braces 15, and hence it is on a lower plane than the shelf 25.

A shelf 29 is preferably of the rectangular configuration and has its ends supported from brackets or slings, each of which com-

prises a member 30 having a hook 31 that is canted with respect to the longitudinal axis of the member, and each hook is adapted to embrace one of the posts above the brace 5 15, in order that the brace will limit the downward movement of the member 30. The said member 30 is furthermore provided with an angularly disposed extension 32 which underlies its main portion and which 10 constitutes the support for the shelf 29, it being shown that when the shelf is applied to the extensions of the slings, its inner edge bears against the post so that a bracing action results which serves to retain the parts 15 in their assembled relations to one another.

When the device is set up with the parts assembled as heretofore described, it may be used as supports for clothes or the like which have been ironed, or it may be otherwise employed.

If the device is to be converted into a support for an ironing board, the shelving and the separate fixtures associated with the shelving will be removed, and the upper 25 braces 16 will then be employed as a support for an ironing board 33. The under side of the ironing board may have pairs of cleats 34 and 35, the cleats of each pair being in spaced relation to each other to 30 form a clearance for the brace in order that longitudinal movement of the ironing board will be prevented, even though pressure is applied to it, as in the act of ironing. The ironing board is further provided with a 35 handle 36 having its ends extending through the board, and this handle may be secured in place in any appropriate way.

The clothes rack which is associated with the shelving and frame heretofore described 40 is hingedly mounted on one of the posts, and the said rack, in the present embodiment of the invention, comprises two end members 37 and 38 connected together by bars 39 which bars are pivotally connected to the 45 end members in order that the rack may be partially folded when it is to be stored. The rack is hingedly connected to one of the posts by the brackets 40, each of which comprises

a shank adapted to be anchored to the end piece 38 and a ring or loop 41 is adapted to 50 encircle the post so that the rack may be swung to the position shown in Fig. 1 or to the position shown in Fig. 2, and be capable of other adjustments, according to the wishes of the user.

A device of the character indicated may be inexpensively manufactured and as it is capable of a wide range of use, it will form a desirable equipment as an article of household furniture.

I claim:

1. In combination furniture for household use, a frame comprising end posts arranged in pairs, braces connecting the posts of each pair, means for holding the pairs of end posts in spaced relation to each other, a series of shelves supported on the frame in successively advanced positions, and on different planes, slings having hooked ends embracing two of the end posts and suspended thereon, said slings having inwardly turned ends constituting shelf engaging elements, and a shelf resting on said inwardly turned ends and bearing against the posts whereby the inward movement of the slings is limited, as and for the purpose described.

2. In combination furniture for household use, a frame having end posts arranged in pairs, braces connecting the posts of each pair, the said posts extending above the braces, a shelf adapted to rest on the upper brace and having an aperture at each end, each of which receives an end post, stirrups suspended from the said braces at each end, a shelf supported by the stirrups, a shelf having recesses in its edges fitted to posts of the frame and supported on other of said braces, and slings having hooks encircling two of the end posts, each of said slings having angularly disposed extensions underlying the main body of the sling constituting supports for a shelf, and a shelf on said extensions having its edges braced against the posts encircled by the hooks of the slings.

CHARLES E. KUHN.
